DESIGN.

S. V. SMITH.
WAGON BODY AND TOP.

No. 28,457.

Patented Apr. 5, 1898.

UNITED STATES PATENT OFFICE.

SAMUEL VANOSTEN SMITH, OF PHILADELPHIA, PENNSYLVANIA.

DESIGN FOR A WAGON BODY AND TOP.

SPECIFICATION forming part of Design No. 28,457, dated April 5, 1898.

Application filed January 25, 1898. Serial No. 667,938. Term of patent 14 years.

To all whom it may concern:

Be it known that I, SAMUEL VANOSTEN SMITH, of Philadelphia, in the county of Philadelphia and State of Pennsylvania, have invented and produced a new and original Design for a Wagon Body and Top, of which the following is a full, clear, and exact description.

Reference is to be had to the accompanying drawings, forming a part of this specification, in which—

Figure 1 represents a side elevation of a body and top embodying my new design, and Fig. 2 a rear end elevation.

The design consists in the wagon body and top having the configuration and ornamentation shown, to wit: The body A or lower por-

tion of the structure is rectangular and oblong, and from the said body rises the top B, simulating a greenhouse and being paneled, as shown, the top further having a pitch-roof C, 20 which is also paneled and projects forwardly beyond the body A, the ridge of the roof having rising therefrom a longitudinally-ranging panel D.

I claim—

The design for a wagon body and top herein shown and described.

SAMUEL VANOSTEN SMITH.
